United States Patent Office

Des. 196,774
Patented Oct. 29, 1963

196,774

COMBINED PROPORTIONER AND DISPENSER

Phillip Donald Sanborn, Chardon, Ohio, assignor to
Lehn & Fink Products Corporation, New York, N.Y.,
a corporation of Delaware

Filed July 12, 1962, Ser. No. 70,892

Term of patent 14 years

(Cl. D91—3)

FIG.1

FIG.3

FIG.2

FIG.4

FIG.5

FIGURE 1 is a top plan view of a combined proportioner and dispenser showing my new design;

FIGURE 2 is a front elevational view thereof;

FIGURE 3 is a side elevational view thereof, the opposite side being substantially the same;

FIGURE 4 is a cross-sectional plan view thereof taken through line 4—4 in FIGURE 2, specifically showing the semi-circular recessed wall portion thereof;

FIGURE 5 is an isometric rear view thereof.

I claim:

The ornamental design for a combined proportioner and dispenser, substantially as shown and described.
